INSULATED PORTABLE CONTAINER

Herbert M. Piker, Wyoming, Ohio, assignor to The Hamilton-Skotch Corporation, Hamilton, Ohio, a corporation of Ohio

Filed May 27, 1964, Ser. No. 30,181

Term of patent 14 years

(Cl. D58—17)

FIG. 1 is a front elevational view of an insulated portable container, showing my new design.

FIG. 2 is a side elevational view thereof, the side opposite that being a mirror image thereof and the rear having substantially the same appearance on the lower side wall thereof;

FIG. 3 is a top plan view thereof.

FIG. 4 is an enlarged, fragmentary, sectional view as seen from line 4—4 on FIG. 1.

FIG. 5 is an enlarged, fragmentary, sectional view as seen from line 5—5 on FIG. 3.

FIG. 6 is an enlarged, fragmentary, sectional view as seen from line 6—6 on FIG. 1.

I claim:

The ornamental design for an insulated portable container, substantially as shown and described.
